CLAIM

The ornamental design for a precious stone cut short corners crown design having 41 facets, showing my new design as shown and described.

DESCRIPTION

FIG. 1 is a top plan view of a precious stone cut short corners crown design having 41 facets showing my new design;

FIG. 2 is a side view; and,

FIG. 3 is a bottom plan view.

The broken line showing of the pavilion of a gemstone is included for the purpose of illustrating environmental matter and forms no part of the claimed design.
